MUFFLER

William B. McLeod, Los Angeles, Calif.

Application August 3, 1942, Serial No. 453,326

10 Claims. (Cl. 181—48)

This invention relates to improvements in mufflers and constructions designed to silence the exhaust of internal combustion engines, particularly airplane engines or engines used on aircraft.

A primary object of the invention is to provide an improved muffler construction which is so designed as to enable the handling of the exhaust gases to effectively silence the noise and at the same time create a minimum amount of resistance so that there will be little or no pressure in the exhaust manifold of the engine due to the presence of the muffler which pressure, if present, would reduce the efficiency of the engine.

More specifically, an object of the invention is to provide a muffler consisting of an outer shell having an inlet and an outlet with a straight unobstructed passage therethrough from the inlet to the outlet and which has a series of annular cavities formed therein that are closed except around the mentioned passage forming chambers in which that portion of the exhaust gases that flows directly through the passage may radially expand and thereafter flow toward the outlet. By thus forming a series of such cavities or chambers expansion of the gases is permitted but the transmission of the noise to the outlet is greatly reduced and substantially eliminated.

Another object of the invention is to provide a muffler having the above-mentioned characteristics wherein the wall forming the outer sides of the cavities is in spaced relation to the interior of the shell whereby a substantial portion of the exhaust gases may flow around these cavities between the outer wall thereof and the interior of the shell and be subsequently directed toward the outlet. In this manner, an opposed turbulence is created in the gases which tends to neutralize itself adjacent the center of the muffler before passing into the outlet. By this construction although the exhaust gases enter the muffler in a succession of bursts or puffs the noise is effectively eliminated and the gases are quieted so that when they issue from the outlet they issue in the form of a relatively steady stream as distinguished from the incoming bursts or puffs.

With the foregoing and other objects in view, which will be made manifest in the following detailed description and specifically pointed out in the appended claims, reference is had to the accompanying drawing for an illustrative embodiment of the invention, wherein:

Figure 1 is a longitudinal vertical section through the muffler embodying the present invention;

Fig. 2 is a vertical section taken substantially upon the line 2—2 upon Fig. 1;

Fig. 3 is a vertical section taken substantially upon the line 3—3 upon Fig. 1;

Fig. 4 is a perspective view of one of the forwardly directed conical baffles; and

Fig. 5 is a perspective view of one of the rearwardly directed conical baffles.

Referring to the accompanying drawing wherein similar reference characters designate similar parts throughout, 10 indicates the inlet from the 15 exhaust manifold of an internal combustion engine. 11 indicates the outlet from the muffler. The muffler comprises a shell in the form of an outer sheet metal cylinder 12 equipped at its ends with end caps 13 and 14 which may be welded or otherwise secured thereto. On the interior of the shell there is disposed a layer of 20 insulating material 15 such as shredded asbestos. This insulation is maintained against the interior of the cylinder 12 such as by a woven wire screen 16. Bars 17 extend longitudinally through the shell from end to end thereof and rest against the interior of the screen 16. These bars are preferably three in number although their number may be varied. Adjacent the forward end 25 of the muffler there is a series of forwardly directed conical baffles, each of which as illustrated in Fig. 4, consists of a frusto-conical portion 18 having at its apex an aperture 19 and at its back a cylindrical skirt 20. Radially extending arms 30 35 21 may be formed integral with the skirt or may be attached thereto and these arms are in turn welded or otherwise secured to the longitudinally extending bars 17. The baffles are arranged one behind the other so that the apertures 19 are in alignment with each other and with the inlet 10. The edge of the skirt of each baffle is welded or otherwise secured to the juncture of the conical portion of the succeeding baffle with its skirt such as is indicated by the welds 22. The skirt portions 20 thus cooperate to define a cylindrical wall around the forwardly directed conical baffles, which cylindrical wall is in spaced relation to the interior of the shell the inner surface of which is formed by the skirt 16. Thus, a series of outwardly and rearwardly divergent annular cavities 23 are formed around the central passage formed by the aligned apertures 19.

At the back of the muffler there is a series of rearwardly directed conical baffles 24. These baffles are in the form of frusto-conical portions

having apertures 25 at their apices that are in alignment with each other with the outlet 11 and with the apertures 19. Radial arms 26 are formed integral with these baffles or are otherwise secured thereto and are welded or are otherwise secured to the longitudinally extending bars 11. The rear edge of the rearwardly directed baffle 24 is preferably welded to the outlet pipe 11.

The operation of the improved muffler is as follows. The exhaust gases entering the muffler from the exhaust manifold of the internal combustion engine enters through the entrance or through the inlet 10 in a series of puffs or bursts. A fraction of these gases pass straight through the straight unobstructed passage afforded by the aligned apertures 19 these gases tending to quickly radially expand. Opportunity for expansion is afforded by the annular cavities or chambers 23 which are closed except for the space surrounding the passage provided by the apertures 19. Thus, each puff or burst of incoming exhaust gases has a portion that passes through the apertures 19 and in so doing it merely expands radially into the chambers 23 compressing the residual gas or air that may be present therein. Between consecutive puffs or bursts this compressed gas in each chamber can expand back into the straight, central, longitudinal passage as indicated by the reversely bent arrows in these chambers. The remainder of the incoming gas that enters the muffler from the inlet 10 is spread by the foremost conical baffle and as indicated by the arrows, this remainder flows rearwardly between the skirt 20 and the screen 16, flowing between the braces or arms 21. That portion of the gas that has passed through the straight central passage through the muffler finally encounters the series of rearwardly directed baffles which converge toward the central passage. These gases when encountering these converging surfaces have turbulences developed therein as indicated by the arrows on Fig. 1. Those gases which passed on the outside, that is between the skirt 20 and the screen 16, also encounter these converging baffles and as these gases are directed inwardly they have a similar turbulence generated therein. The turbulence on diametrically opposite sides of the rearwardly directed baffles is in the opposite direction so that when these opposed turbulences meet in the rear portion of the straight central passage formed by the aligned apertures 25, the opposed turbulences tending to neutralize each other with the result that the exhaust gases when they enter the outlet 11 issue therefrom in a relatively steady stream as distinguished from the incoming puffs or bursts.

By this construction the noise attendant the exhaust gases issuing from the exhaust manifold is substantially eliminated. However, as there is no obstruction within the muffler, back pressure on the interior of the inlet 10 and the exhaust manifold is reduced to such an extent as to be negligible. Consequently, there is no back pressure created by the muffler in the exhaust manifold that would reduce the efficiency of the engine.

While the muffler in its preferred form is cylindrical it will be understood that it may be given any other desired or preferred cross-sectional shape. Thus rectangular, hexagonal, or triangular or oval shapes might be employed if desired.

In the event that the baffles on the interior of the muffler become burned or corroded with use, it is possible to effect an easy replacement thereof.

by merely removing one of the end caps 13 or 14. When the end cap is removed the baffles which are all mounted on the longitudinally extending bar 11 can be withdrawn by sliding these bars longitudinally from within the skirt 16. Thus all baffles can be removed together as a single unit and a substitute unit may be instantly inserted and the end cap replaced.

From the above-described construction it will be appreciated that the improved muffler is of relatively simple design, inexpensive to manufacture, and is highly efficient in its operation, reducing the noise but at the same time conducting the gases in such a manner as to prevent the creation of back pressure in the exhaust manifold. Although the invention has been illustrated as incorporated in a muffler that is connected to the exhaust manifold it will be appreciated that it would be possible, in certain instances to embody the invention directly on the interior of the exhaust manifold itself.

Various changes may be made in the details of construction without departing from the spirit or scope of the invention as defined by the appended claims.

I claim:

1. A muffler comprising means providing an outer shell having an inlet adjacent one end and an outlet adjacent the other, there being a continuous straight unobstructed passage through the shell from the inlet to the outlet, means providing a series of outwardly extending cavities within the shell adjacent the inlet, said cavities being closed except around said passage, said cavity providing means being in spaced relation to the inner wall of the shell and from the inlet whereby a portion of the gases entering through the inlet may pass directly into the passage and the remainder of the gases flow around the cavity providing means toward the outlet.

2. A muffler comprising means providing an outer shell having an inlet adjacent one end and an outlet adjacent the other, there being a continuous straight unobstructed passage through the shell from the inlet to the outlet, means providing a series of outwardly extending cavities within the shell adjacent the inlet, said cavities being closed except around said passage, said cavity providing means being in spaced relation to the inner wall of the shell and from the inlet whereby a portion of the gases entering through the inlet may pass directly into the passage and the remainder of the gases flow around the cavity providing means toward the outlet, and converging means in the shell adjacent the outlet for converging the gases toward said passage before passing into the outlet.

3. A muffler comprising means providing an outer shell having an inlet adjacent one end and an outlet adjacent the other, there being a continuous straight unobstructed passage through the shell from the inlet to the outlet, means providing a series of outwardly extending cavities within the shell adjacent the inlet, said cavities being closed except around said passage, said cavity providing means being in spaced relation to the inner wall of the shell and from the inlet whereby a portion of the gases entering through the inlet may pass directly into the passage and the remainder of the gases flow around the cavity providing means toward the outlet, said shell being insulated.

4. A muffler comprising means providing an outer shell having an inlet adjacent one end and an outlet adjacent the other, there being a con-

tinuous straight unobstructed passage through the shell from the inlet to the outlet, means providing a series of outwardly extending cavities within the shell adjacent the inlet, said cavities being closed except around said passage, said cavity providing means being in spaced relation to the inner wall of the shell and from the inlet whereby a portion of the gases entering through the inlet may pass directly into the passage and the remainder of the gases flow around the cavity providing means toward the outlet, converging means in the shell adjacent the outlet for converging the gases toward said passage before passing into the outlet, and means connecting the cavity providing means and converging means enabling them to be removed from the shell as a unitary structure.

5. A muffler comprising means providing a shell having an inlet and an outlet, a series of conical baffles having aligned apertures disposed in the shell, said baffles being directed forwardly toward the inlet, and means providing a wall around the baffles in spaced relation to the interior of the shell providing a space in communication with the inlet through which a portion of the gases entering the inlet may flow.

6. A muffler comprising means providing a shell having an inlet and an outlet, a series of forwardly directed conical baffles having aligned apertures disposed in the shell, and means providing a wall around the baffles forming therewith a series of circular cavities open only at the passage formed by the aligned apertures, said wall cooperating with the shell to form a space surrounding the baffles that is open to both the inlet and the outlet.

7. A muffler comprising means providing a shell having an inlet and an outlet, a series of forwardly directed conical baffles having aligned apertures disposed in the shell, and means providing a wall in spaced relation to the interior of the shell around the baffles forming therewith a series of annular cavities open only at the pas-

sage formed by the aligned apertures, the space between the wall and the shell being open to both the inlet and the outlet.

8. A muffler comprising means providing a shell having an inlet adjacent one end and an outlet adjacent the other, a series of conical baffles within the shell having aligned apertures opposite the inlet, said baffles being directed forwardly toward the inlet, means providing a wall around the baffles in spaced relation to the shell, said wall cooperating with the shell to provide a space open to the inlet and the outlet through which a portion of the gases entering the muffler through the inlet may pass.

15. A muffler comprising means providing a shell having an inlet adjacent one end and an outlet adjacent the other, a series of conical baffles within the shell having aligned apertures opposite the inlet, said baffles being directed forwardly toward the inlet, means providing a wall around the baffles in spaced relation to the shell, said wall cooperating with the shell to provide a space open to the inlet and the outlet through which a portion of the gases entering the muffler through the inlet may pass, and a series of conical baffles in the shell having aligned apertures opposite the outlet, the last-mentioned series of baffles having their edges in spaced relation to the walls of the shell and being directed rearwardly toward the outlet.

20. A muffler comprising means providing a shell having an inlet adjacent one end and an outlet adjacent the other, a series of conical baffles within the shell having aligned apertures opposite the inlet, said baffles being directed forwardly toward the inlet, means providing a wall around the baffles in spaced relation to the shell, said wall cooperating with the shell to provide a space open to the inlet and the outlet through which a portion of the gases entering the muffler through the inlet may pass, the interior of the shell being lined with insulating material.
